UNITED STATES PATENT OFFICE.

WARREN C. REES, OF SOMERVILLE, MASSACHUSETTS, ASSIGNOR TO ASEPTIC SERVICE COMPANY, OF BOSTON, MASSACHUSETTS, A CORPORATION OF MAINE.

WATER-CLOSET SEAT.

1,171,644.

Specification of Letters Patent. Patented Feb. 15, 1916.

Application filed October 12, 1915. Serial No. 55,540.

To all whom it may concern:

Be it known that I, WARREN C. REES, a citizen of the United States, and resident of Somerville, in the county of Middlesex and State of Massachusetts, have invented 5 certain new and useful Improvements in Water-Closet Seats, of which the following is a specification.

The present invention relates to aseptic 10 water closets of the type in which a clean surface is always provided on the seat by the use of a paper, or other aseptic or sanitary covering, which is shifted and renewed after each use of the closet.

15 More particularly the invention has relation to that type of closet in which the seat is formed with two members located at opposite sides of the toilet bowl and each projecting toward the center thereof when in use, and being raised or withdrawn when not in use. Seats of this character are exhibited in my prior Patents No. 1,092,392, 20 wherein the seat members are withdrawn into a casing when not in use, and No. 25 1,156,175 dated October 12, 1915, in which the seat members are raised when not in use. In toilets of this type the seat members are placed in operative position, that is in a substantially horizontal position pro-

30 jecting over the toilet bowl, immediately prior to each use of the toilet, and are retained in that position by locks or latches; such latches are released when a weight is placed upon the seat, as in the ordinary use 35 of the toilet, and springs or equivalent automatic means are provided for returning the seat members to their inoperative (respectively withdrawn or raised) positions as soon as the weight has been removed. Hitherto in seats of this type the locks or latches and the means for releasing such locks under pressure of the superimposed weight, for the two sections, have been entirely independent of one another, whereby it has been 40

45 possible by confining the weight wholly to one section, to release the lock of that section, and allow that section alone to be withdrawn or raised upon removal of the weight, leaving the other section in the substantially 50 horizontal or operative position. It has been found in practice that in the use of such seats just this result has frequently occurred, by reason of the user having supported his weight wholly or mainly on one 55 of the seat sections, without applying suffi-

cient pressure to the other section to release the lock of the latter. Such a result is undesirable and objectionable for various reasons, among which are the greater difficulty of drawing the covering strip, prior 60 to the next use of the toilet, about the seat section which has remained in the operative position, and the liability of tearing or breaking the strip where the same is of paper, particularly if it should have happened to become wet.

The object of the present invention is to provide an improved form of latching or locking means for a two section seat of the sort indicated, together with efficient controlling means and connections by which the application of a weight on either seat member will release the lock of the other seat member, insuring the retraction of both seat members into the inoperative position after 70 each use of the closet, even though the weight of the user may have been supported wholly by one of the seat members.

A further object is to provide means for correlating the movement of one member 80 to that of the other, compelling the two members to move in substantially identical fashion, and preventing the raising or lowering of either alone.

With the foregoing explanation of purpose in mind, the principles and scope of the invention may be sufficiently understood from the following detailed description of one possible embodiment in concrete form 85 of these principles.

90 Figure 1 is a front elevation of a toilet with one form of my invention applied thereto. Fig. 2 is a plan view on an enlarged scale of the parts to which my present invention is confined, located below the line 2-2 of Fig. 1. Fig. 3 is a front elevation of the parts shown in Fig. 2, illustrating such parts in the position occupied 95 thereby immediately prior to use. Fig. 4 is a similar view showing the parts in the position of use, that is, in the position occupied after a weight has been applied to the seat. Fig. 5 is a view of parts at the left of line 5-5 in Fig. 3. Fig. 6 is a detail view of the latch, seen from the point of view of Fig. 5, but in the position assumed 100 when the seat is placed as in Fig. 4.

The same reference characters indicate the same parts in all the figures.

Referring to the drawings, 10 represents 110

a toilet bowl and 11, 11 represent the members which together form the seat of the toilet and which may be called for the purposes of this description seat members or sections. These members are duplicates of one another and are each pivoted by a pintle 12 to a casing 13. Such casings are located at opposite sides of the toilet bowl and are connected by crossbars at the front 10 and rear of the bowl, respectively, so that a rigid structure is produced which may be supported in any suitable or desired way, for example, as shown in my patents aforesaid, or as in my Patent No. 1,165,123 dated 15 Dec. 21, 1915. The casings 13 extend above the rim of the bowl and the pintles 12 are at such a height that the seat members, when placed in a horizontal or substantially horizontal position, may extend 20 over the sides of the bowl toward the median plane thereof, and therefore toward one another, their inner edges being separated by a space sufficiently wide for the purposes of the toilet.

25 Fig. 1 shows the seat members in the position assumed just before use. They are brought into this position by a treadle bar 16 which forms the connecting part and operating part of two lever arms 17, 17, each of which is pivoted to a bracket 18 depending from one of the casings 13. The latter, by the way, may be understood to contain a supply spool or roll of paper and a take-up roll on which the paper is wound 30 after being passed over and under the adjacent seat member. The elements and mechanisms contained within the casings, as well as the means by which the seat members are normally held in the withdrawn or raised, that is inoperative, position may be of any character, such for example, as shown in my prior Patents No. 1,092,392 dated April 7, 1914 or No. 1,156,175 dated October 12, 1915. As such elements 35 and mechanism are fully described in the aforesaid patents, repeated illustration and description thereof are not deemed to be necessary in this specification, since the present invention relates wholly to the locking and releasing means and equalizing connections between the seat members, and is not concerned otherwise with the operation of the seat members, nor with the aseptic covering or the means for supplying and taking up the latter. It is sufficient to 40 be understood that the seat members are under a constant pressure or impulse tending to withdraw them from the operative position to the inoperative raised, or retracted, position, and that the treadle 16 is an operating means adapted to bring them into the operative position against the yielding resistance of such force or impulse. When the seat members are brought into 45 this position, they are held by latches, of

which there is one for each member. One of these latches has been fully illustrated in detail in the drawing; and such illustration suffices for both, since the two are preferably duplicates of one another. 70

The latch consists of a plate 19 and a supporting arm 20 on a rock shaft 21, and having a shoulder 22 which is adapted to engage a pin 23 carried by a bracket 24 which is secured to the under side of the seat section. The said rock shaft is located directly in back of the crossbar 14 and is rotatably mounted near its ends in bearing blocks 25 secured to said crossbar. The arms 20 are conveniently formed by bending up the extreme ends of the rod which forms the rock shaft, although this particular detail of construction may be varied without departing from the invention. A spring 26 is coiled about the rock shaft 21 85 and is engaged therewith by one of its ends passing into a hole 27 in the rock shaft as shown in Fig. 4. The other end 28 is carried out straight and is caused to bear on the crossbar 14, as shown in Fig. 5. The pressure of the spring tends to hold the rock shaft and arms in the position shown in Fig. 5, where each arm bears against a stop finger 29 formed on a plate which is attached on the inner side of the bearing block 25. As thus arrested by the stop finger, the shoulder 22 of the latch crosses the path in which stud 23 is carried by the movement of the seat to operative position. The face or edge 30 of the latch plate extending from the inner limit of the shoulder 22 to the outer limit of the latch is inclined to the plane in which the stud and seat move, whereby the stud on striking such edge is adapted to displace the latch and to pass by the shoulder. In other words, the latch has a cam portion by which it may be dislodged by the action of the stud from the path of the latter. This cam surface, as will be noted from Fig. 5, extends also 100 beyond the outer end of the seat, so that the seat in its further movement beyond the locked position, under the weight of the occupant, may act with the same effect to dislodge the latch from the path of the stud, as illustrated in Fig. 6. 110

When the seat reaches the operative position, in which it is locked by the coöperation of the latch shoulder 22 and stud 23, it rests on a spring elevated post or plunger 31 which slides in a vertical guide 32 formed on the crossbar 14, and is supported by a spring 33 which reacts against a foot 34 projecting downward and inward from the crossbar under the plunger rod. This post 125 is adapted to yield against the resistance of spring 33 until the seat strikes the upper end of the guide 32 as shown in Fig. 4.

The bracket 24 previously described as carrying the stud 23 projects somewhat be- 130

yond the outer end of the seat and has a finger 35 extending above the lower surface of the seat and close to the outer end of the latter, and is formed with a convex inclined wedge or cam surface 36, as shown best in Figs. 5 and 6. The latch carries a yielding guide pin 37 which is pressed toward the bracket 24 and, in the normal position of the latch, is so located that it bears 10 against the surface of the bracket when the seat comes into the position for use. In the preferred construction here shown pin 37 is contained in a sleeve 38 secured to the latch plate 19 and passing through the same. 15 A spring 39, indicated in Fig. 3, surrounds a reduced part of the pin and is confined between a shoulder thereon and a complementary internal shoulder at the outer end of the sleeve, in a well known manner. The 20 pin has a head 40 at the end of its reduced part which is prevented from passing through the sleeve and thereby limits the movement of the pin in the direction toward which it is pressed by the spring. 25 When the seat is brought into position for use, the locking stud 23 passes over the latch and becomes engaged therewith. Both seat members are brought into this position simultaneously and are both so locked. If 30 now a person sits on the seat the latter is depressed until it reaches the positive stop provided by the guide 32. In so moving, the outer edge of the seat bears on the cam surface of the latch and shifts the latch outwardly, as shown in Fig. 6, thereby carrying the spring pressed guide pin 37 beyond the outer or forward edge of the bracket 24. As soon as the pin has passed beyond the 35 outer edge of this bracket it is pressed out 40 by its spring 39 and thereby is caused to overlap the bracket, and is prevented by the outer edge thereof from returning to the locking position. Now when the weight of the occupant is removed from the seat, 45 the latter is raised by the means provided for that purpose, such, conveniently, as described in my prior patents above specified. In this rising movement of the seat, the latch is held by the engagement of the guide 50 pin with the outer edge 36 of the bracket away from the locking stud 23 until after the latter has passed the latch shoulder. When the bracket has fully passed by the 55 guide pin, the latch is returned by the constantly acting spring 26 to the normal position. It matters not whether in the use of the seat both sections or only one have been pressed upon, because the rigid connection between the latches of the two studs, 60 through the rock shaft 21, insures the release of both latches when either one is released in the manner last above described, and the weight of the occupant on either seat section is operative to release the latch of that section. Thus even though the weight of the

user should be applied only to one section, both are equally released and allowed to return afterward to the inoperative position.

In such conditions as referred to in the foregoing description, it is also desirable 70 that the seat section which is not pressed upon should not rise and either cause inconvenience to the user or pass into the inoperative position and so leave uncovered that part of the bowl which it is intended to 75 guard. For this purpose and also to equalize the movement of the two seat sections in the ordinary operation, I have provided a connection between the sections, which consists of a rock shaft 41 extending across 80 the toilet and supported by lugs 42 on the casings 13, and having at each end an arm 43 which is connected by a link 44 with the adjacent seat section, such section having a lug or bracket 45 carrying a pivot stud 85 46 contained in an eye 47 in the link. The extreme positions of the rock shaft, arms 43 and links 44, are shown by full and dotted lines, respectively, in Fig. 5. It will be evident that in all positions the arms are so 90 oblique to the links that movement of either seat section independently of the other section is impossible.

Referring again to the seat lock and particularly to Figs. 3 and 4, attention is called 95 to the fact that the bracket 24 and its cam finger 35 are in concentric relation to the pivot 12 of the seat; that is, these parts of the bracket are inclined to one another and are substantially equally distant from the 100 pivot. They are in effect chords of adjacent arcs of the same circle having the seat pivot as its center. Further, that the guide pin 37 is substantially radial to the same axis and has its spring impelled movement 105 in the direction of its length; and that the plane in which the guide pin is shifted by swinging of the rock arm 20 is parallel to said axis. These relations are established in order that the guide pin will remain in 110 engagement with the cam edge of the bracket throughout the length of the latter, without requiring to be made excessively long or to have an excessive range of spring pressed movement, and also to avoid obliquity of 115 action of the pressures exerted by these members, one upon another, so far as possible. The extreme end of the bracket is bent back or out, that is, at an inclination to the radius of the seat pivot so that it will 120 pass over the end of the guide pin 37 and crowd the latter back as the seat comes into operative position.

I desire it to be understood that the descriptive terms hereinbefore used in this 125 specification have been chosen wholly with regard to their aptness to the particular illustrative embodiment of the invention and without intent to limit the scope of the invention to elements or means answering the 130

most restricted definitions of such terms. My invention is to cover by the appended claims the principles herein involved, in whatever specific form of mechanical means 5 they may be embodied.

What I claim and desire to secure by Letters Patent is:

1. A water closet seat, comprising independent sections or members, locks for holding the seat members in operative position, and means for releasing the lock of either section when that of the other section is released.

2. A water closet seat comprising two separate sections, a lock for each section adapted to hold the same in operative position, means controlled by pressure of a weight on either section for releasing the lock thereof, connections whereby the release of either 20 lock also releases the other.

3. In combination with a seat composed of distinct and separate parts and adapted to occupy either a substantially horizontal position for use or a retracted and inoperative 25 position, a separate lock for holding each section in operative position, and means for releasing the locks of both sections when either section is sat upon.

4. A seat composed of distinct sections 30 adapted to be respectively raised and lowered, means acting on said sections tending constantly to raise them, latches arranged for automatic engagement with the seat sections when lowered to retain them in lowered position, said latches having means for causing their disengagement when the seat is sat upon, means whereby the release of either latch causes the other to be released, and connecting means from one seat section 35 to the other for preventing raising of either while the other remains lowered.

5. The combination with a toilet, of seat sections pivotally mounted at opposite sides of the toilet and extending therefrom toward one another when in the position for use, said sections being raisable about their pivots, a latch for each section arranged to hold the same in the lowered position, connecting means between said latches for causing similar actuation of either when the other is actuated, and connections between the sections arranged to prevent raising or lowering movement of either relatively to the other.

6. In combination with a toilet, a seat comprising two sections pivoted at opposite sides of the toilet extending toward one another when in position for use and being raisable into inoperative position, pivoted 55 latch arms mounted adjacent to each seat section beneath the same, latch abutments carried by said sections engageable with said latch arms, and a rock shaft connecting the latch arms of both sections whereby movement of both latch arms in unison is assured.

7. In combination with a toilet, a seat comprising two sections pivoted at opposite sides of the toilet extending toward one another when in position for use and being raisable into inoperative position, pivotally 70 mounted latch arms mounted adjacent to each seat section beneath the same, latch abutments carried by said sections engageable with said latch arms, a rock shaft connecting the latch arms of both sections 75 whereby movement of both latch arms in unison is assured, a second rock shaft having two rock arms, each adjacent to one of the seat sections, and a link joining each rock arm to the adjacent section.

8. In combination with a toilet, a seat consisting of two sections pivoted at opposite sides of the toilet and movable from a substantially horizontal position extending toward one another from their pivots, into 85 a raised or inoperative position, a latching abutment carried by each seat section, a latch adjacent to the abutment of each section when the latter is in the position for use, a rock arm carrying each latch, and a 90 rock shaft to which said rock arms are rigidly joined, each latch having a cam face and each seat section having a complementary portion adapted to bear on said cam face and displace the latch from locking position 95 upon depression of the seat below its operative position.

9. The combination with a shiftable seat adapted to be lowered into position for use and raised into inoperative position, of a 100 latch for holding the seat in operative position, comprising a member having a shoulder and arranged to swing in a plane substantially parallel to the path of movement of the seat, and having a cam portion, said seat having a locking abutment adapted to engage said cam portion to displace the latch when approaching operative position, and to pass under the latch shoulder when in such position, and the seat being arranged to bear on said cam surface and displace the latch from locking position when carried beyond the position for use, and the seat and latch having also complementary means for retaining the latch out of the path of the locking abutment until such abutment has passed the latch upon the withdrawal of the seat to inoperative position.

10. The combination with a seat having 110 a latch engaging abutment, of a latch having a shoulder to interlock with said abutment and having an inclined cam surface adjacent thereto, the seat being formed with a part to bear on said cam surface and displace the latch from locking position, a cam member projecting from the seat adjacent to the latch and having a cam edge, and a 115 guide pin carried by the latch yieldingly pressed against said cam member when the 120

latch is in locking position, and being displaced beyond the edge of said cam member when displaced by coaction of the seat with the cam surface of the latch.

- 5 11. The combination with a pivotally mounted seat, of a bracket extending therefrom in the general direction of movement thereof, a stud carried by said bracket and arranged transverse to such direction of
10 movement, a latch pivotally mounted to swing in a plane substantially parallel to the axis of the seat and having a shoulder arranged to overlie said stud, having also a cam edge at the side thereof next to the
15 seat, which cam edge extends across the nearest edge of the seat, a yielding spring-pressed pin carried by said latch and pressed toward the bracket, being normally held back thereby when the seat is in locked
20 engagement with the latch, said bracket having a guiding edge at its outer limit beyond the end of the seat.

12. The combination with a pivoted seat, of a bracket secured to the under side of said
25 seat adjacent to the edge thereof, having a finger projecting beside said edge, the bracket and finger being inclined to one another in

the relation of chords of adjacent arcs of the same circle having the axis of the seat as a center, a stud carried by the bracket near 30 the outer end thereof and arranged approximately radial to said axis, a latch arm pivoted to swing in a plane approximately parallel to said axis and provided with a shoulder arranged to pass between said stud 35 and the surface of the seat when the latter is in locking relation, and having an inclined surface at its end next to the seat passing beyond that edge of the seat beside which the aforesaid bracket finger lies, a 40 pin carried by the latch arm, being movable endwise and resiliently pressed toward said bracket, being in contact therewith and arrested thereby when the seat is in locked relation, the outer edge of the bracket and 45 the cam edge of the latch being so disposed and proportioned that pressure by the seat edge on the latch cam is adapted to swing the latch arm far enough to carry its spring-pressed guide pin beyond the edge of the 50 bracket.

In testimony whereof I have affixed my signature.

WARREN C. REES
